UNITED STATES PATENT OFFICE.

GEORGE E. RIDER AND CLARENCE A. GLEASON, OF KANSAS CITY, MISSOURI.

PAPER-FOLDING AND WRAPPER-APPLYING MACHINE.

Application filed August 14, 1922. Serial No. 581,643.

To all whom it may concern:

Be it known that we, GEORGE E. RIDER and CLARENCE A. GLEASON, citizens of the United States, and residents of Kansas City, Jackson County, Missouri, have invented a certain new and useful Improvement in Paper-Folding and Wrapper-Applying Machines, of which the following is a complete specification.

10 This invention relates to paper folding and wrapping machines, and has for its primary object to produce a machine for efficiently and neatly interfolding a newspaper or magazine and wrapper together as rapidly as the printed papers are discharged from a press; a further object being to produce a machine adapted for automatic adjustment of the paper-folding elements, to accommodate papers of different size as regards the number of sheets and the diameter of the papers when folded or rolled.

With these general objects in view, the invention consists in certain novel and useful features of construction and combinations of parts as hereinafter described and claimed; and in order that it may be fully understood, reference is to be had to the accompanying drawings, in which:—

Figure 1 is a top plan view of a machine embodying the invention.

Figure 2 is a side elevation of such machine.

Figure 3 is a front elevation of the machine.

Figure 4 is a vertical section taken on the line IV—IV of Figure 1.

Figure 5 is a fragmentary elevation with parts broken away to more clearly disclose the newspaper pick-up mechanism.

Figure 6 is a detailed section showing the vacuum connection for the newspaper pick-up devices.

Figure 7 is a detail sectional view of one of the newspaper pick-up devices.

Figure 8 is a similar view of the wrapper pick-up devices.

Figure 9 is a detail vertical section showing the wrapper vacuum connection.

Figure 10 is an inverted view of a slidably mounted pawl forming a part of the adhesive-applying mechanism; and Figure 11 is a diagrammatic view showing steps in the folding and wrapping operation.

In the said drawings where like reference characters identify corresponding parts in all of the figures, 1 indicates the sides of a

framework leading from or arranged adjacent a printing press (not shown) from which newspapers N or the like, in a substantially horizontal stack, are fed standing edgewise and flatly together in any suitable manner upon suitable supports 2 until arrested by the abutment of the upper portion of the foremost sheet with a stop 3 extending from one of the sides of the framework to the other.

An air exhausting or vacuum tube 4 connects with the tubular arm 5 of a head 6 journaled upon a tubular rock shaft 7 mounted in the framework and provided with a port 8 adapted to be alternately opened and closed to communication with the tubular arm 5 through rocking movement imparted, as hereinafter described, to the said shaft.

Shaft 7 is provided preferably at two intermediate points, with ports 9 communicating with tubular arms 10 rigidly secured on said shaft, and said arms are provided with arcuate extensions 11 extending concentrically of shaft 7 and adapted to be sealed at their outer ends by pressing against the foremost paper, so that when said arms rock away from the stack or column of papers, they shall draw the foremost paper with them and withdraw it from the stack or column.

The shaft 7 is provided with a crank-arm 12, pivotally connected by a link 13 with a crank-arm 14 on a transverse shaft 15, and mounted upon the latter is a pair of feed rollers 16 provided with peripheral recesses 17. A shaft 18 parallel with and above shaft 15, is equipped with a similar pair of rollers 19 provided with peripheral recesses 20; the rollers 16 and 19 being adapted to cooperate in the feeding operations of the newspapers, as hereinafter more particularly explained, and the rear shoulders of the rollers, with respect to the direction of rotation, formed by the recesses 17 and 20, engage the rear edges of the papers and in effect "kick" them forward to position for proper engagement by a tucker, hereinafter described.

Rigidly secured on one end of shaft 15 is a miter gear 21 meshing with a similar miter gear 22 secured on a shaft 23 journaled in any suitable manner on the sides of a second framework 24, extending at right angles to the direction of travel of the newspapers and at the discharge end of the first mentioned framework. Secured

on shaft 23 is an eccentric 25 engaging an eccentric strap 26, and the latter is connected to arms 27 rigid with an inverted U-shaped tucker 28 for engaging the news-papers as they are fed horizontally one at a time, by the rollers 16 and 19, and imparting to them a preliminary fold and tucking them in this condition down between a pair of feed rollers 29 journaled 10 in boxes 30 set in the sides of framework 24; one set of boxes of the rollers being relatively movable toward the other set by springs 31 to provide for the proper passage between them of the newspapers regardless of the bulk thereof when in folded condition.

The rollers 29 are geared together exterior to framework 24, by conventional staggered toothed gear wheels 32 and 33 to insure 20 transmission of power from one to the other regardless of the relative position of the rollers, and one of the latter is driven from shaft 23 through the sprocket wheel 34 on shaft 23, chain 35 and sprocket wheel 36 on the shaft of said roller. Underlying the other rear roller 29 is a cooperating roller 37 of reduced diameter centrally for a purpose hereinafter explained, and the shaft of roller 37 is equipped with a gear 25 wheel 38 similar to and meshing with gear wheel 33. Boxes 39 in which the shaft of roller 37 is journaled, receive the pressure of springs 40 whereby the roller 37 may move away from the overlying roller 29 30 to accommodate the passage of folded papers of different bulk. Rearward of rollers 29 is a roller 41 of the same type as roller 37, and the shaft of roller 41 is equipped with a gear wheel 42 of the same 35 type as and meshed with gear wheel 33, so that roller 41, shall cooperate with the adjacent roller 29 after the latter and the underlying roller 37 have cooperatively functioned. The shaft of roller 41 is journaled in boxes 40 45 which under pressure of springs 44^a, hold roller 41 in yielding relation to the adjacent roller 29, for the same reason rollers 29 bear a yielding relation to each other.

To primarily make the second fold in the 50 paper and incidentally insert the end of a wrapper in such fold and tuck the paper between the cooperative rollers 29 and 37, and after the paper has emerged from between said rollers, again fold and tuck it up between said rollers 29 and 41, the following mechanism is provided:

A hollow shaft 44 (see Figure 9), is journaled in parallel relation to and below roller 37, and is provided with an air port 60 45 adapted for communication at times with a chamber 46 of a collar 47 connected to an air exhausting tube 48. The shaft is equipped with tucker 49 comprising tubular arms in communication with the interior of the shaft 44, and an arc-shaped blade having pas-

sages 50 communicating at their inner ends to the passages of the arms and terminating at their outer ends in mouths 51 at the peripheral side and near the front edge of the tucker. To rock the shaft, it is provided 70 with a crank-arm 52 pivotally connected by a link 53 to a wrist pin 54 on sprocket wheel 34, and arm 52 has a spring-actuated slide-able pawl 55 adapted when the tucker 49 is withdrawn, to engage a tooth of ratchet 75 wheel 56, and, as the tucker advances, impart rotary movement to said ratchet wheel, a spring-actuated detent 57 insuring arrest of the ratchet wheel as the pawl leaves the latter, and holding it against backward 80 movement so that it shall always be properly positioned for actuation by the pawl. The ratchet wheel is secured to a shaft 58 journaled in framework 24, and equipped with a rotary brush 59 partly submerged in 85 a liquid paste or adhesive container 60, and held against the lower edge of the foremost of a stack of wrappers 61 supported on a shelf 62 and adapted to be fed toward the brush by hand pressure or by a follower not shown, of any conventional type employed in paper stack feeding devices. The shelf has corner arms 62^a to limit feeding 90 adjustment of the wrappers and to hold the foremost ones from buckling under engagement by said tucker as it returns to "pick-up" or lowered position.

It will be noted by reference to Figure 4, that the arc-shaped portion of tucker 50 is of such form and proportion that it co-operates with arms 62^a in guarding against the foremost wrapper or wrappers curling over at the upper edge and that when said tucker is in its withdrawn position as indicated in dotted lines, its front or face is bearing against the upper part of the foremost wrapper and that the latter seals the mouths 51 at the instant the advance movement of said tucker begins, because at such instant, the shaft 44 disposes its port 45 in communication with the air-exhausting tube 48. The wrapper is therefore drawn upward from the stack, and at the start of such action, the brush rotates and spreads an adhesive on the face of the wrapper at 105 the lower edge thereof.

The shaft 44 has a second crank arm 63 pivotally connected by a link 64 to the crank arm 65 of a shaft 66 journaled in framework 24 and equipped with a tucker 67 for operating upwardly between roller 41 and the adjacent roller 29 to start the third and final folding operation to be completed by said rollers, the parts being so arranged that the tucker 67 moves upward against the paper after the completion of the second folding thereof, and applies pressure midway the width of the paper to fold or buckle it upward and force it between the said rollers 29 and 41, the folding operation inci- 115 120 125 130

dentially folding the wrapper tucked end-
wise in the paper as the second folding op-
eration occurred, but leaving the adhesive-
coated end projecting sufficiently to com-
pletely encircle the folded paper and over-
lap an exposed portion of the wrapper for
adhesion thereto, as hereinafter explained,
it being noted in this connection that al-
though the paper is folded in passing roller
10 37 and again folded in passing roller 41, it is
not contaminated by paste or adhesive, as
the reduced central portions of the said roll-
ers accommodate the wrapper, and the adhe-
sive side of the latter never contacts with the
15 working face of any of the rollers. The ad-
hesive coated end of the wrapper remains
projected from the paper until the final fold
of the latter is accomplished, and is then
forced down upon a portion of the wrapped
20 wrapper itself, this occurring as the folded
and wrapped paper is rotated as it is conveyed
to the discharge point of the machine, as
hereinafter explained. In this connection it
will be understood that as the tucker 49 in-
25 serts the front end of the wrapper into the
folding paper, and the latter is gripped be-
tween roller 37 and the overlying roller 29,
the port 45 moves out of communication
30 with the vacuum tube 48, and the wrapper
is therefore released preliminary to the re-
turn of the said tucker to pick up another
wrapper for a repetition of the operation de-
scribed.

To feed the folded paper to the discharge
35 end of the machine, and wrap or wind the
projecting end of the wrapper completely
around the paper and cause it to adhere to
itself and thus hold the paper in folded con-
dition, the following mechanism is pro-
40 vided:

An endless traveling feeder extending
from a point above the roller 41 to the dis-
charge end of the machine consists of a
45 transverse shaft 68 journaled in bearings 69
on the sides of framework 20, a pair of
sprocket wheels 70 overlying the extremity
of roller 41, chains 71 connecting said wheels
50 with larger sprocket wheels 72 secured on a
second transverse shaft 73, journaled in the
sides of a skeleton frame consisting of the
longitudinal side bars 74 and transverse con-
necting bars 75. Said frame is mounted at
55 one end on shaft 68 and at the other on a rod
76 journaled in slidable bearings 77 mounted
on the rear end of the side of framework 24,
and the said feeder chains are provided with
spaced teeth 78 for rolling and imparting
60 travel to the interfolded paper and wrapper
as and after the latter passes over the
roller 41.

Secured on one end of shaft 73 is a
sprocket wheel 79 of greater diameter than
the sprocket wheels 72, said sprocket wheel
79 is connected by an endless chain 80 with a
65 still larger sprocket wheel 81 mounted on

one end of the shaft of the rearmost of the
pair of rollers 29. It will thus be seen by
reference, particularly to Figure 2, that the
lower strand of the feed chain mechanism
travels toward the discharge end of the ma-
70 chine and is adapted for cooperative action
with the underlying roller 41.

Arranged within the framework 24 and in
a lower plane than the said traveling feeder
and slightly inward of the vertical plane of
the chains of the latter, is a pair of longitudi-
nally-extending bars 82, mounted at their
75 rear end on angle brackets 83 secured to the
sides of said framework, and at their front
ends on a cross-bar 84 secured to the sides of
the framework. Below said bars 82 and ex-
tending transversely of the framework and
journaled therein are cross shafts 85
equipped with a plurality of star wheels 86
occupying vertical planes between the chains
71 and the adjacent bars 82, and said shafts
85 are geared together by a chain 87 and
sprocket wheels 88 so that the star wheels
shall turn together and at the same speed.
80

As the newspapers pass successively from
engagement with roller 29, and an idler roller
89, rearward thereof to assist roller 41
in the feeding operation, the latter under co-
operative action with the feeding mecha-
nism impels the papers toward the star
90 wheels, the travel being positive because of
the pressure of the teeth of the feeder
chains. The papers are caught by the bars
82 as the former clear the roller 41, and are
pushed by said teeth against the upwardly-
projecting arms of the pairs of star wheels
in the order in which the latter are encoun-
tered, and thus impart rotation to said
wheels and eventually ride clear of the free
ends of such arms. As this occurs with
100 each star wheel the paper clearing the same
has attained a position over the arm of the
next star wheel, about to swing upwardly
and rearwardly beyond the bars 82, and the
following arm of the star wheel turned by
105 a particular paper, then engages such paper
and continuing its movement until it has
reached or approximately reached the up-
wardly-projecting arm of the next star
wheel, it being understood that the feed
110 chains cooperate in this action and keep
the paper in continuous movement towards
the rear end of the machine and eventually
discharges it off the discharge end of the
bars. In this action it will also be observed
115 that the folded papers are in effect rolled
along the bars 82 and thereby better main-
tained in substantially rolled condition for
the purpose of giving the adhesively-coated
end of the wrapper sufficient time to dry and
120 thus guard against the expansion and un-
wrapping of the paper.

To complete the wrapping of the paper,
that is to cause the projecting end of the
wrapper to wind completely around the pa-
125

per and become affixed to the body portion of the wrapper, we provide a flexible strip 88^a attached at one end to the shaft 68 so that the latter shall be free to turn without affecting the said flexible strip, which it is to be noted, will be of heavy canvas, rubber or the like and under which the papers as they successively pass the roller 41 are adapted to pass, the said flexible strip serving as the papers are rolled forward, to in effect, apply a wiping pressure on the projecting end of the wrapper at the outer side thereof so as to complete the winding of such end around and cause it to adhere to the body portion of the wrapper and thus securely hold the wrapped paper in folded or rolled condition.

In Figure 4, a series of papers in rolled or wrapped condition are indicated in dotted line as traveling upon the supporting bars 82 and are adapted to be engaged by strip 88^a which will rest upon all of the papers in succession, said strip resting upon the shafts 85 or some of them when the machine is empty. To make the wrapping action clearer reference is to be had to Figure 11, which indicates diagrammatically the successive folds of the paper and the application thereto of a wrapper. The first figure to the left shows the paper as it appears after the first fold downward between the roller 29. The next figure to the right shows the paper after the second fold has been made and the end of the wrapper has been tucked into the fold. The next figure to the right shows the paper after the third or final fold has been made and shows the end of the wrapper still projecting.

The fourth figure shows the paper wrapped or rolled and the wrapper wound completely around the same and affixed to itself. In said figure *a* indicates the original fold point, *b* the second fold point and *c* the third or final fold point, the paper and wrapper being indicated in single lines, that is with no thickness, as the clearest method of illustration.

As the function and operation of the various parts have been set forth in detail, we believe that it is not necessary to recapitulate the same in a general summary, other than to state that the various operations are so timed that the tuckers 28, 50 and 67 perform their functions in quick succession, the first named tucker returning to position and being ready to make the first fold in a second paper as the tucker 50 completes the second fold of the preceding paper and starts back to its original position to pick up a second wrapper. The third tucker moves upward and engages the paper preliminary to making the third fold at the instant the second tucker starts on its reverse movement. The operation of the feeding mechanism is at a greater rate of speed

than that of the folding rollers in order to space the papers apart as well as to impart rolling movement thereto as they successively pass out of engagement with the roller 41. They are maintained in properly spaced relation by the star wheels and through the action of the feeder and the flexible strip 88 are caused to roll forward on the bars 82 and have the projecting adhesive-coated ends of the wrapper wound snugly upon them.

From the above description it will be apparent that we have produced a machine embodying the features of advantage set forth as desirable in the statement of the object of the invention, and which is susceptible of modification in various particulars, without departing from the principle of construction and mode of operation involved and without departure from the scope of the appended claims.

We claim:

1. In a machine of the character described, means for moving a wrapper edgewise toward the side of a paper and for starting the folding of the latter with the wrapper partially within the fold, means for completing such folding operation, means for refolding the paper with a portion of the wrapper projecting therefrom, and means for rotating the folded paper to cause the projecting end of the wrapper to overlap and engage the intermediate portion thereof where the same is folded with the paper, but exterior to the latter.

2. In a machine of the character described, means for moving a wrapper edgewise toward the side of the paper and for starting the folding of the latter with the wrapper partially within the fold, means for completing such folding operation, means for starting another folding operation of the paper, means for completing such folding operation, and means for rotating the folded paper to cause the rear end of the wrapper to overlap and engage the intermediate portion thereof, where the latter is wrapped with but exterior to the wrapped paper.

3. In a machine of the character described, means for moving a wrapper edgewise toward the side of a paper and for starting the folding thereof with the wrapper partially within the fold, means for completing such folding operation, means for refolding the paper with a portion of the wrapper projecting therefrom, means for rotating the folded paper to cause the projecting end of the wrapper to overlap and engage the intermediate portion thereof, where the same is folded with but exterior to the paper and means for applying liquid adhesive to the wrapper for sticking the overlapping portions of the same together to hold the paper in folding position.

4. In a machine of the character described, means for moving a wrapper edge-wise toward the side of a paper and for starting the folding of the latter with the wrapper partially within the fold, means for completing such folding operation, means for starting another folding operation of the paper, means for completing such folding operation, means for rotating the folded paper to cause the rear end of the wrapper to overlap and engage the intermediate portion thereof where the latter is wrapped with but exterior to the wrapper paper, and means to fasten together the overlapped portions of the wrapper.

5. In a machine of the character described, means for moving a wrapper edge-wise toward the side of a paper and for starting the folding of the latter with the wrapper partially within the fold, means for completing such folding operation, means for starting another folding operation of the paper, means for completing such folding operation, means for rotating the folded paper to cause the rear end of the wrapper to overlap and engage the intermediate portion thereof where the latter is wrapped with but exterior to the wrapper paper, and means to successively convey the wrapped papers from the point where they are rotated in the operation of the overlapping portion of the wrapper together.

6. In a machine of the character described, a pair of driven feed and folding rollers, means for disposing paper above said rollers, means for giving the paper a preliminary central fold and for tucking the folded portion or edge between said rollers, a driven roller below one of said rollers for cooperative action therewith, means for giving the folded paper as it is fed from said pair of rollers, a preliminary fold and for tucking it at its last folded edge between the superposed rollers, a roller parallel with the uppermost of said superposed rollers, and means for giving the folded paper a preliminary third fold and for tucking the folded edge between the said superposed roller and said roller parallel thereto.

7. In a machine of the character described, means for moving a wrapper edge-wise toward the side of a paper and for starting the folding of the latter with the wrapper partially within the fold, means for completing such folding operation, means for starting another folding operation of the paper, means for completing such folding operation, means for starting another folding operation of the paper, means for com-

pleting such folding operation, means for rotating the folded paper to cause the rear end of the wrapper to overlap and engage the intermediate portion thereof where the latter is wrapped with but exterior to the wrapped paper, means for pasting the overlapped portions of the wrapper together, and means for resting upon the wrapped paper, and tending to smooth and tension the wrapper and insure the adhesion of its outer end to the portion overlapped by such end.

8. In a machine of the character described, means for moving a wrapper edge-wise toward the side of a paper and for starting the folding of the latter with the wrapper partially within the fold, means for completing such folding operation, means for starting another folding operation of the paper, means for completing such folding operation, means for rotating the folded paper to cause the rear end of the wrapper to overlap and engage the intermediate portion thereof where the latter is wrapped with but exterior to the wrapped paper, means for cooperating with the said parallel roller to revolve the folded and wrapped paper, means for applying an adhesive for securing the overlapped portions of the wrapper together, means for resting upon the wrapper paper and tending to tension the wrapper and insure the adhesion of its outer end to the portion overlapped by such end, and means actuated through the wrapped papers to effect their travel to a point of discharge.

9. In a machine of the character described, means for moving a wrapper edge-wise toward the side of a paper and for starting the folding of the latter with the wrapper partially within the fold, means for completing such folding operation, means for starting another folding operation of the paper, means for completing such folding operation, means for rotating the folded paper to cause the rear end of the wrapper to overlap and engage the intermediate portion thereof where the latter is wrapped with but exterior to the wrapper paper, means for applying an adhesive for securing the overlapped portions of the wrapper together, means cooperating with the folding means for imparting travel and rotation to the wrapped paper, and flexible means for resting on the wrapped paper and tending to tension the wrapper and insure its adhesion where fastened together.

In witness whereof we hereunto affix our signatures.

GEORGE E. RIDER.
CLARENCE A. GLEASON.
